UNITED STATES PATENT OFFICE.

JAMES TAGGART, OF BOWLING GREEN, INDIANA.

WIRE FENCE.

SPECIFICATION forming part of Letters Patent No. 339,823, dated April 13, 1886.

Application filed December 28, 1885. Serial No. 186,899. (No model.)

To all whom it may concern:

Be it known that I, JAMES TAGGART, a citizen of the United States, residing at Bowling Green, in the county of Clay and State 5 of Indiana, have invented certain new and useful Improvements in Wire Fences; and I do hereby declare the following to be a full, clear, and exact description of the invention, such as will enable others skilled in the art 10 to which it appertains to make and use the same.

My invention relates to wire fences; and it consists of a portable wire fence made in sections having a lever-post for supporting the 15 wire and stretching the same, as hereinafter more particularly described and claimed.

My invention is illustrated in the accompanying drawings, in which Figure 1 is a front view in elevation of my improvement as 20 a whole, and Fig. 2 a detail showing post and stretching device.

In the drawings, A is a lower portion of a post, which may be metal or wood, sharpened and provided with a shoulder, b, and shank c. 25 B is a flat bar, constituting a lever and the upper part of the post. It is secured to the shank c by means of screw-bolts and washers, as shown at d e, so that its lower end is pivoted thereto just above the shoulder b. The 30 upper end of the bar B is provided with a bolt, f.

G and H are upper and lower double and twisted strands of wire, twisted so as to form loops i at intervals, and by means of the loops 35 at the ends these wires are secured to the upper bolt, f, on the lever-bar B, and to the top bolt, d, on the shank.

L are intermediate stays for the fence, also consisting of a double wire twisted to form 40 loops. These stays are put through the loops i in the upper and lower horizontal strands, and are secured to the upper wire by means of pieces of wire or barbs m.

Both the stays and horizontal wires may be 45 provided with barbs, if desired, or they may be dispensed with.

A section of fence will consist of two posts

and their lever-bars, the horizontal wires, and their stays. Additional horizontal strands of wire may be added, if desired, put through 50 the loops of the stays, and the bars B may be provided with additional holes or bolts to receive them.

To put sections of this fence in position and to stretch the wires, the posts are inserted in 55 the ground, the upper bolt, d, is withdrawn from the shank c, the bar B thrown to one side. The upper wire is then secured to the bar by the upper bolt, f. The bar is then drawn back to a vertical position, when the 60 lower one is attached to the bar by means of the bolt d, and when the bolts are tightened the whole section is held tight and rigidly in place. The bar B may also be used as a lever to aid in extracting the lower part or stump 65 of the post.

By making the lever-bar and post separable either the stump or the bar may be removed and replaced by new parts when the same become worn out or broken.

Having thus described my invention, what I claim is—

An improved fence made in panels, consisting of longitudinal strands of wire to which are secured vertical wires and posts, each of 75 which posts comprises a lower section adapted to be driven into the ground, and having a shouldered recess at its upper end, an upper section pivoted to the lower section in said recess, and provided at its top with a stud on 80 which to secure the upper strand of the panel, and a screw-bolt passed through the two sections above the pivot for attachment thereto of the lower strand of a panel, and at the same time for holding the upper section of the post 85 in a vertical position, as hereinbefore set forth.

In testimony whereof I affix my signature in presence of two witnesses.

JAMES TAGGART.
